CLAIM

The ornamental design for a tool box, as shown and described.

DESCRIPTION

FIG. 1 is a front perspective view of a new design for a tool box;

FIG. 2 is a front view of a new design for a tool box as seen in FIG. 1;

FIG. 3 is a rear view of a new design for a tool box as seen in FIG. 1;

FIG. 4 is a left side view of a new design for a tool box as seen in FIG. 1; right side view being a mirror image; and, FIG. 5 is a top view of a new design for a tool box as seen in FIG. 1.

The broken lines illustrate portions of the tool box and form no part of the claimed design.
